UNITED STATES PATENT OFFICE.

OTTAR S. LEE, OF CHICAGO, ILLINOIS, ASSIGNOR TO THE NYE TOOL & MACHINE WORKS, OF CHICAGO, ILLINOIS, A CORPORATION OF ILLINOIS.

THREADING DEVICE.

Application filed April 20, 1923. Serial No. 633,420.

To all whom it may concern:

Be it known that I, OTTAR S. LEE, a citizen of the United States, residing at Chicago, in the county of Cook and State of Illinois, have invented a new and useful Improvement in Threading Devices, of which the following is a specification.

My invention relates, more particularly, to devices for forming threads on the ends 10 of objects, more particularly pipes and rods; and my primary object is to provide a device which shall be adapted for threading larger pipes by employing thread-cutting chasers, and smaller pipes by employing die blocks, 15 thereby avoiding the necessity of providing separate devices for utilizing the chasers and die blocks in the cutting of larger and smaller objects, respectively.

Referring to the accompanying drawing: 20 Figure 1 is a face view of a structure embodying my invention. Figure 2 is a section taken at the line 2—2 on Fig. 1 and viewed in the direction of the arrows, Figure 3 is a section taken at the line 3 on Fig. 1 and viewed in the direction of the arrows, and 25 Fig. 4 an enlarged section of the body of the device with the chasers positioned therein for use, the section being taken through opposed chasers, with the chasers shown in 30 section.

The particular construction illustrated comprises a ring-like member 3 formed at one end with a peripheral flange 4, its opposite end being screw-threaded, as represented 35 at 5, to receive a ring 6 screwed thereon and forming, with the body of the ring 3 and flange 4, a peripheral annular groove 7 in which a ring 8 is rotatably confined, the ring 3 being internally screw-threaded, 40 as represented at 9. The ring 3 is provided with a series of lugs 10 extending lengthwise of the device and provided in a circumferential series, these lugs terminating, at their outer ends, in a ring-shaped head 11, 45 concentrically disposed relative to the ring 3, the head 11 being provided at intervals with radially-extending set-screws 12, located in threaded openings 13 in the ring 11, these set screws being provided for the purpose hereinafter set forth.

The device also comprises a head 14 comprising a tubular portion 15 externally screw-threaded, as represented at 16, and screwing into the threads 9 of the ring 3, 55 the threads 9 and 16 forming a lead-screw

for the purpose hereinafter explained. The outer end of the member 15 is provided with a series of radiating bosses 17, with webs 18 extending therebetween, the member 15, bosses 17 and webs 18 being preferably integral. The bosses 17 are provided for receiving thread-cutting chasers, such as are commonly used in cutting threads on the larger sizes of pipe, these bosses, to this end, containing radiating grooves 19 for receiving the chasers represented at 100 in Fig. 4 and undercut, as represented at 20, to prevent displacement of the chasers. In order that the chasers may be automatically moved radially outward from the object being threaded thereby, as the threading operation progresses, the ring 8 is provided with a series of pins 21, four of which are shown to correspond with the number of bosses 17, these pins extending parallel with the axis of the device and extending into openings 22 in the bosses 17, in which they have sliding fit. The pins 21 extend into the grooves 19 and are each formed with an inclined surface, extending longitudinally thereof, as shown of the surface 23 of the one of the pins shown in Fig. 3 and the two pins in Fig. 4, the surfaces 23 diverging toward the right hand end of Figs. 2 and 4.

The inner ends of the bosses 17 are substantially straight, these straight end surfaces, represented at 24, being preferably disposed at substantially right angles to each other, with the surfaces 24 of the diametrically-opposed bosses being parallel and substantially equally spaced apart, whereby the space bounded by the end surfaces 24 of the bosses 17 is such as to receive a die block such as is commonly used for forming threads on objects such as pipes or rods. A die block of the kind referred to is represented at 25, it being formed of a body portion 26 of square form containing a central aperture 27 into which the cutter ends of the thread-cutting segments 28 secured in the body-portion 26, in radiating position thereon, extend.

The device also comprises releasable means for holding the die block 25 in the space bounded by the bosses 17, these means being of any suitable construction, those shown comprising a plate 29 adapted to be laid across the outer face of the die block 25 and provided with rearwardly-projecting portions 30 and 31, the portion 30 having a

flange 32 adapted to overlap the rear face of one of the webs 18, and the portion 31 being provided with a screw 33, preferably pointed at its inner end, which is adapted to engage the rear surface of the one of the webs 18 diametrically opposed to the web which is engaged by the flange 32, the portion of the plate 29 where it overlaps the block 25 being apertured as represented at 34.

For the threading of objects, such as pipes or rods, from say of one inch diameter upwards, the die block clamping means, and also the die block 25, would be removed from the position shown in Figs. 1 and 2, and the chasers 100, such as are commonly employed in die stocks, and of a length and form suitable for operating on the particular diameter of object to be threaded, inserted into the grooves 19. The operator then selects a bushing of an internal diameter substantially the same as the external diameter of the object to be threaded, and inserts this bushing into the opening in the ring-shaped member 11, the form of bushing being substantially that shown at 35 in Figs. 2 and 4, the opening through this bushing being represented at 36. The device is then slipped over the end of the pipe to be threaded, to cause the chasers 100 in the grooves 19 to extend adjacent the extremity of the pipe at which the threads are to be produced, the bushing 35 surrounding the pipe, and the operator then tightens up the set screws 12, which extend through openings 37 in the bushing, to set them rigidly against the object to be threaded, rigidly securing the ring 3 against rotation on the pipe. The operator then rotates the member 14 carrying the chasers, handles 38 inserted into socket members 39 formed as part of two of the bosses facilitating rotation of the member 14, the teeth of the chasers cutting into the pipe to be threaded. The threaded connection between the part 15 and the ring 3 operates, when the member 14 is rotated in clockwise direction in Fig. 1, to cause the member 14, with the chasers 100, to move to the right in Figs. 2 and 4 and consequently lengthwise of the pipe, thus serving to cause the chasers to cut a thread on the pipe corresponding with the thread 16. As the member 14 moves to the right in Figs. 2 and 4, as stated, the pins 21 being held by the rotatable ring 8, against lengthwise movement, the chasers 100 are, by reason of the inclined surfaces 23 of these pins and against which the outer ends of the chasers bear, permitted to move radially outward sufficiently to effect the tapering of the thread produced on the object, as will be well understood in the art.

When it is desired to thread an object of smaller diameter the chasers are removed

from the grooves 19 and a die block 25, adapted for the threading of an object of the particular size to be threaded, is applied to the device to the position shown in Figs. 1 and 2, and as hereinbefore explained, the webs 18 being preferably formed with seating lugs 18^a against which the die block bears at its rear face to insure the positioning of the die block at a right angle to the axis of the device, and the clamping means of which the plate 29 is a part, applied to position thereon as shown, the operator substituting a bushing, such as the bushing 35 and containing an opening 36 of the desired diameter, for the bushing previously used, the set screws 12 being screwed into the ring 11 sufficiently far to hold the bushing 35 against displacement, but not far enough to grip the object.

In the use of the device with the die block 25, the device is slipped over the end of the object to be threaded and the entire device rotated on the pipe, the cutting segments 28 producing the desired thread on the object, it being understood that, as these die blocks are commonly provided, they operate to cut the thread on the object without requiring any additional means for feeding it along the pipe, such as the lead screw means 9 and 16 and which is required in the case of the use of chasers as commonly provided and hereinbefore described. It is desirable that when the die-block 25 is in place and the plate 29 secured in clamping position, the block 25 may shift in a direction crosswise of the axis of the device, in the event that the axis of the die block is out of alignment with the axis of the pipe, in order that the die block may align with the pipe, this being preferably provided for by so proportioning the parts of the device that the space in which the die block 25 is located is of slightly larger dimensions than the die block, and to permit the block to slip as stated the distance from the outer seating-faces of the seating lugs 18^a to the outer faces of the bosses 17 is slightly greater than the thickness of the die block 25, and the plate 29 is provided of such shape and size that it will fit flatwise against the outer faces of the bosses 17, as shown.

It will be understood from the foregoing that instead of requiring separate devices for receiving and holding chasers and die blocks, respectively, for the threading of larger and smaller pipes, one receiving and holding device only is necessary, the workmen using chasers or die blocks with the same device, depending upon the size of the object to be threaded.

It may be stated, as regards the particular form of means shown for holding the die block 25 in place, that as these means are bodily removable, though not indispen-

sable to the carrying out of my invention, the device is rendered entirely free of any parts the presence of which might be objectionable when the device is being used with 5 chasers in the grooves 19.

While I have illustrated and described a particular construction constituting an embodiment of my invention, I do not wish to be understood as intending to limit it there- 10 to as the same may be variously modified and altered without departing from the spirit of the invention.

What I claim as new, and desire to secure by Letters Patent, is:

15 1. A thread-cutting device comprising a member containing an opening and adapted to hold thread-cutting chasers in operative position at said opening, those surfaces of the portions of said member at which said 20 chasers are held, and which are disposed about said opening, being disposed at substantially 90° to each other and in opposed relation, adapting said member to receive a die block within the space bounded by 25 said portions, and means for releasably holding the die block in said position on said member.

2. A thread-cutting device comprising a member containing an opening and pro- 30 vided with bosses radiating from said opening, said bosses being adapted to hold thread-cutting chasers in operative position at said opening, the inner end surfaces of said bosses being so disposed as to afford 35 a space adapted to receive a die block which bears at its rear face against portions of said member between said bosses, and means opposing the outer face of the die block for releasably holding the latter in position 40 on said member.

3. A thread-cutting device comprising a member containing an opening and adapted to hold thread-cutting chasers in operative position at said opening, the portions of 45 said member at which said chasers are held being so disposed as to adapt them to receive into the space therebetween a die block, and means for releasably holding the

die block in said position on said member, the parts being so constructed and arranged 50 that the die block may shift in a plane at an angle to the axis of the device.

4. A thread-cutting device comprising a member containing an opening and pro- 55 vided with bosses radiating from said opening, said bosses being adapted to hold thread-cutting chasers in operative position at said opening, the inner end surfaces of said bosses being so disposed as to afford a space adapted to receive a die block which 60 bears at its rear face against portions of said member between said bosses, the distance from the outer faces of said bosses to the portion of said member which opposes the rear face of the die block being 65 greater than the thickness of the die block to permit the die block to aline with the axis of the pipe by shifting in a direction crosswise of the axis of the device and a plate on said member opposing the outer 70 face of the die block and bearing against the outer faces of said bosses, for releasably holding the die block in position on said member, said die block being shiftable in a 75 plane at an angle to the axis of the device.

5. A thread-cutting device comprising a member containing an opening and adapted to hold thread-cutting chasers in operative position at said opening, the portions of 80 said member at which said chasers are held being so disposed as to adapt them to receive in the space therebetween a die-block, and means for releasably holding the die-block, in said position on said member comprising a clamping plate extending across 85 the outer face of the die-block and provided with rearwardly-projecting portions one of which is equipped with a flange adapted to overlap the rear face of said member and the other being provided with a screw adapt- 90 ed to engage the rear face of said member at a point opposite to said overlapping flange, whereby to releasably hold said die-block in place.
